CLAIM

The ornamental design for a safety belt, as shown and described.

DESCRIPTION

FIG. 1 is a top perspective view of a safety belt, showing my new design;

FIG. 2 is a bottom perspective view thereof;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is an enlarged top plan view;

FIG. 9 is an enlarged bottom plan view;

FIG. 10 is a perspective view showing the safety belt in a use state;

FIG. 11 is an enlarged detail view of area 11 in FIG. 1; and, FIG. 12 is an enlarged detail view of area 12 in FIG. 10

The broken lines in the drawings illustrate the portions of the safety belt, which form no part of the claimed design. The dash-dot-dash broken lines encircling the enlarged views are for annotative purposes only and form no part of the claim thereof.
